TREAT T. PROSSER, OF CHICAGO, ILLINOIS.

Letters Patent No. 72,677, dated December 24, 1867.

IMPROVED BRUSH AND MOP-HEAD.

The Schedule referred to in these Letters Patent and making part of the same.

TO ALL WHOM IT MAY CONCERN:

Be it known that I, TREAT T. PROSSER, of the city of Chicago, in the county of Cook, in the State of Illinois, have invented a new and improved Brush and Mop-Head combined; and I do hereby declare that the following is a full and exact description thereof, reference being had to the accompanying drawings, and to the letters of reference marked thereon, in which like letters represent like parts.

Figure 1 is a perspective view.

Figure 2, the lever-beam *d d* of fig. 1.

Figure 3, a section of the screw-ferrule *b* and lugs *c c* of fig. 1.

To enable others skilled in the art to make and use my invention, I will proceed to describe its construction and operation.

Letter *a*, fig. 1, is the handle; letters *b b*, a screw-ferrule; *c c*, the lugs thereon, which hold and operate the journal-end of the lever *d d*, which has a journal at one end to operate freely between the lugs on the ferrule, and a large hole, so as to receive the screw-ferrule and allow it to freely operate therein. Near the centre of the lever-beam, fig. 2, *ff* are two trunnions, around which the ends of the mop-wires are bent; and the end of the beam *ll* is of a suitable form to clasp the brush when between it and the two projections *kk* on the head *h h*, as seen in fig. 1, at the bottom of the figure.

After selecting a handle, such as are in common use, I prepare it for the castings or irons, by boring a hole into the end for the screw that attaches it to the head, and drive suitable pins into the handle to operate the screw-ferrule, and through it the lever-beam.

The irons being cast, they are in readiness to be put together, which is done in the following manner: The lever-beam is inserted between the lugs, as shown in fig. 1, *c c*, and the screw-ferrule in the aperture or hole in the beam. The handle is inserted into the screw-ferrule, and screwed down through it so as to receive the head, (a washer being placed between the end of the handle and the head,) and a screw is passed through the head and the washer, and firmly screwed into the handle, leaving the screw sufficiently loose in the head and washer to freely turn therein. The wire *gg*, fig. 1, being arranged in position, as shown, and twisted around the trunnions on the lever-beam, the handle is completed and ready for use. By putting several pins into the handle to operate the ferrule, a much shorter ferrule can be used than otherwise.

From this arrangement it will be readily seen that a cheap, durable, and complete article is produced, doing away with bolts and rivets to such an extent as to make the compound brush and mop head about as simple and cheap as either of those for mops or brushes, and much more desirable.

After thus fully describing the construction and operation of my invention, what I claim as new, and desire to secure by Letters Patent, is—

1. The combination of the movable ferrule with the pins in the handle of the mop, all as for the purposes set forth.
2. The combination, with the handle of a brush and mop-holder, of a ferrule, provided with screw-threads upon its interior surface, and with lugs on the outside, all as for the purposes set forth.
3. The combination of the ferrule *b b*, provided with lugs *c c*, and the lever *d d*, all as for the purposes set forth.
4. The lever-beam *d d* with movable fulcrum, serving to hold the brush at one end, and also to operate the wire that holds the mop, all as for the purposes set forth.

Witnesses:
